CONTAINER HAVING INTEGRAL TEAR STRIP

Frank F. Osmers, Maywood, N. J.

Application October 4, 1951, Serial No. 249,775

1 Claim. (Cl. 220—54)

1

This invention relates to cans or containers, such as the so-called vacuum-packed cans which are opened by the removal of a tearing strip formed in the cylindrical wall thereof.

Sheet metal containers made of tin plate and like material embodying an integral tearing strip in the cylindrical wall of the container are well known. As heretofore constructed upon winding the tearing strip in a slotted key provided for that purpose, the tearing strip tends to work off the end of the key in the form of a spiral as it is wound on to the key, rather than form a compact cylinder as intended. This frequently takes place even though the user exercises care to hold the key against longitudinal movement relative to the can. Such undesired working off of the tearing strip from the key in the form of a spiral has a number of objections among which may be mentioned:

1. The lateral edges of the tearing strip are rough and sharp and may result in accidental injury and damage.

2. Complete severance of the tearing strip from the can is rendered more difficult.

It is among the objects of this invention to provide a container made with a tearing strip so designed that the tearing strip is caused to wind in desired cylindrical form on the key minimizing, if not completely eliminating, any possibility of the tearing strip riding off the end of the key to form an undesired spiral strip.

Other objects and advantages of this invention will be apparent from the following detailed description thereof.

In the accompanying drawing forming a part of this specification and showing, for purposes of exemplification a preferred form of this invention without limiting the claimed invention to such illustrative instance,

Figure 1 is a fragmentary perspective view showing the top portion of a vacuum-packed can embodying this invention; this figure shows the tearing strip partially removed from the can and wound on the key in the act of effecting opening of the can;

Figure 2 is a vertical section taken in the plane passing through line 2—2 of Figure 1; and

Figure 3 is a vertical section taken in the plane passing through line 3—3 of Figure 1.

In the drawing 10 indicates a vacuum-packed can of sheet metal, such as tin plate, comprising a tubular body 11, top member 12 and bottom member (not shown) in the interests of permitting disclosure of the top portion of the can, where the invention resides, on a larger scale

5 than would otherwise be possible. Both the bottom member and the top member 12 may be secured to the tubular or cylindrical body 11 in any conventional manner. As shown in the drawing, the top 12 is secured to the tubular body 11 by a joint 13 formed by interfolding the marginal edges of the top about the marginal edge of the tubular body 11. The side edges of the body 11 may be joined in a lock and lap side seam as conventional.

10 Disposed at the upper end of can 10 is an internal collar band 14, the lower and upper portion of which fit snugly in place against the inside surface of the tubular body 11. The upper edge 15 of collar 14 terminates in an inwardly bent edge curl 16. If desired, edge 16 may be spaced from the inside of top 12 a distance equal to the width of tearing strip 17, although it need not be so spaced. When so spaced upon removal of 15 tear strip 17, when the can is closed the top 12 of the cover thus formed rests on edge 16 and lower edge 18 of the cover extends to a point indicated by the reference character 19. Lower edge 20 of collar 14 is secured by an outwardly 20 extending bead 21 formed in the tubular body 11 and in the lower edge portion of collar 14. Thus the lower edge 20 of collar 14 is locked to the tubular body 11 near the upper edge thereof.

25 The intermediate portion of collar 14 is formed with a container-encircling channel or circular depression 22 of a height slightly greater than the width of tearing strip 17 and a depth approximately equal to the radius of the circle of the cylinder formed by completely winding the 30 tearing strip in the desired manner on the key 25. For tin plate cans having a 5" outside diameter and a 3½" height of the type now commonly used in the vacuum packing of coffee in one pound quantities employing a tearing strip of from ½" to ¼" wide, the depth of circular 35 depression 22 may be from ¼" to ½", preferably about ¼". The circular channel or depression 22 in the collar 14 should be so dimensioned that it accommodates successive convolutions of 40 the tearing strip as wound on key 25 and the key moves about the outer periphery of the can. In this way riding off of the tearing strip from the end of the key is minimized, if not completely 45 prevented. This result will be achieved even though the depth of the circular depression 22 is not sufficient to accommodate the last one or two convolutions of the tearing strip, and it will be understood that this invention includes constructions in which the circular depression 22 is

50

of a depth to accommodate all but the last few convolutions of the tearing strip 17.

Tearing strip 17, as best shown in Figure 2, is disposed directly opposite circular depression 22 and is defined and set off in the tubular body 11 by a pair of parallel score lines 23, 24 formed in the tubular body 11 and along which the tubular body is torn when the tearing strip is removed by the opening key 25. These score lines 23 and 24 are so formed that the tear strip can readily be removed from the tubular body 11 by a pulling motion. As indicated in Figure 2, they extend substantially completely through the thickness of the tubular body 11 so weakening this body in the portion thereof where the score lines are formed that the tear strip can readily be removed once the free end of the tear strip is engaged and pulled upwardly and wound on the key so that subsequent turning movement of the key exerts a pulling action on the tear strip, as shown in Figure 1. The free end of the tear strip is formed with a tongue which as conventional extends beyond the body side seam and is adapted to be engaged by the opening key 25 for opening the container by tearing the tear strip out of the tubular body 11, as clearly shown in Figure 1.

In this invention when the tongue of the tear strip is inserted in the opening of the key 25 and the key wound counterclockwise, the tear strip winds on the key being torn from the tubular body 11; the score lines 23 and 24, as above noted, so weaken the tubular body 11 that the tear strip is readily removed therefrom by a pulling action thereon exerted by the key winding the strip on the key. As successive convolutions are wound on the key the vertical leg of the key remains in substantially the same relative position to the can and is not displaced laterally relative thereto by the successive convolutions forcing the key away from the side wall of the can, as in prior constructions. In this invention successive convolutions of the tear strip collecting on the key

are accommodated by the circular depression 22 so that substantially no force is exerted on the key which tends to move it laterally relative to the can. Furthermore, the top and bottom walls of the circular depression 22 tend to guide the tear strip to cause it to wind on the key to form a compact cylinder as shown on Figure 1.

Since different embodiments of the invention could be made without departing from the scope of this invention, it is intended that all matter contained in the above description or shown in the accompanying drawings shall be interpreted as illustrative and not in a limiting sense.

What is claimed is:

15 A cylindrical container comprising a tubular body and top and bottom members sealing said tubular body, a tearing strip in said tubular body near the top thereof and adapted to be engaged by a key and wound thereon for removal of the tear strip, an internal cylindrical collar having its lower edge secured to said tubular body below the lower edge of said tearing strip, and an inwardly extending container-encircling channel in said collar, said channel having substantially 20 parallel side walls separated a distance slightly greater than the width of said tearing strip and said channel being of a depth equal to a plurality of thicknesses of said tearing strip to accommodate successive convolutions of said tearing strip 25 when wound upon said key in the removal of said 30 tearing strip from the tubular body to effect opening of said container.
